OF SYRACUSE, NEW YORK, A CORPORATION OF NEW YORK

LOOSE LEAF BINDER

Application filed November 1, 1929. Serial No. 404,044.

This invention relates to a new and improved loose leaf binder and is in part a continuation of my co-pending application for improvements in loose leaf binder, filed 5 September 23, 1929, Serial No. 394,536.

This invention is particularly directed toward that type of loose leaf binder in which the opposed prongs of the binder are carried on opposed back members which back members are hingedly connected together.

In using binders of this character, it frequently becomes necessary to move the back members about their hinge so that the opposed prongs will be moved from each other 15 to permit manipulation of the sheets in the binder or to permit sheets to be added to or removed from the binder.

Binders of this type are usually quite large in size and quite heavy and in addition the 20 covers are usually covered with leather or canvas.

When this is the case, it is difficult to move the back member of the binder on the table or desk on which it is supported because 25 there is a considerable amount of friction between the back members and the table or desk upon which they rest.

When the back members of a binder are in the closed position and it is desired to open 30 them by moving the back members about their hinge, of necessity, the portions of the back members which are in contact with the supporting table will be moved towards each other along the table surface.

35 Similarly when the back members are in the open position and are then moved to the closed position, those portions of the back members which are in contact with the table will be moved away from each other along 40 the surface of the table.

The main object of my invention is to provide a loose leaf binder of such a type that the friction between the back members of the binder and the surface of the table or desk 45 upon which it is supported will be minimized to the greatest possible extent so that the movement of such back members in relation to each other will be facilitated.

Another object is to provide a binder of 50 such construction that the main body of the

binder will be at all times supported out of contact with the surface of the table or desk on which it is supported.

Other objects and advantages relate to the size, shape and arrangement of parts all as 55 will more fully appear from the following description taken in connection with the accompanying drawings in which:—

Figure 1 is a perspective view of my improved binder in the closed position. 60

Figure 2 is a section on line 2—2 of Figure 1.

Figure 3 is a section, partially in full, on line 3—3 of Figure 2.

Figure 4 is an end elevation, partially 65 broken away, of my improved binder with the back members in the closed position.

Figure 5 is an elevation similar to Figure 4 with the back members in a partially 70 open position.

It will be understood that my invention may be used with various types of binders and with binders having prongs of different types and having different types of actuating and locking mechanism, but for the purpose 75 of describing my invention I have here shown a binder comprising a back member 1 hingedly connected to a second back member 2 by a piano hinge 3.

In back member 1, I provide a plurality, 80 one only here being shown, of spaced arcuate prongs 4, and in back member 2, I provide a plurality, one only here being shown, of arcuate prongs 5 in spaced relation and in staggered relation to the prongs 4 carried 85 on back member 1.

A cover 6 is hingedly connected to one edge of back member 1 as by a piano hinge 7 and a cover 8 is hingedly connected to back member 2 by a piano hinge 9. 90

Both back members 1 and 2, as here shown, are approximately rectangular in cross-section with the piano hinge 3 located at their rear inner longitudinal edges.

One the rear outer longitudinal edge of 95 back member 1, I provide spaced rollers 10 and 11 and on the rear outer longitudinal edge of back member 2, I provide spaced rollers 12 and 13.

As perhaps may best be seen from Figure 4, 100

the size and position of the rollers just described is such that when the back members 1 and 2 are in the closed position they will be raised a distance above the top of the table 5 or other support indicated at —a— so that only the rollers themselves will be in contact with such supporting surface.

The rollers carried on back member 2 are mounted in a manner identical to the way in 10 which the rollers are mounted on back member 1 so that a description of the mounting of the rollers 10 and 11 on back member 1 will be a description of the mounting of the rollers 12 and 13 on back member 2.

15 As perhaps may best be seen from Figures 2 and 3, I provide in the outer bottom longitudinal edge of back member 1 and enclosed therein a shaft 14 which has one end secured in position by a clip 15 secured in 20 back member 1 and which has its other end secured in back member 1 by a clip 16.

Adjacent one end of back member 1 a portion is cut away as indicated at 17, and in 25 spaced relation thereto and adjacent the opposite end of back member 1, a similar portion is cut away as indicated at 18.

The shaft 14 spans the cut-away portions 17 and 18.

To secure the shaft 14 firmly in position 30 with relation to the cut-away portions 17 and 18, I provide on shaft 14 a clip 19 adjacent the inner end of the cut-away portion 17, the clip 15 being positioned adjacent the outer end of the cut-away portion 17.

35 Similarly, I provide a clip 20 adjacent the inner end of the cut-away portion 18, the clip 16 being positioned adjacent the outer end of the cut-away portion 18.

The rollers 10 and 11 are preferably 40 formed of rubber and are provided with internal bushings 21 and 22 preferably of brass.

The internal diameter of the bushings 21 and 22 is such that the rollers 10 and 11 may 45 rotate freely on the shaft 14.

Roller 10 is positioned on shaft 14 in the cut-away portion 17 which is provided to permit the rotation of roller 10 on shaft 14.

Similarly, roller 11 is positioned on shaft 50 14 in the cut-away portion 18.

For the purpose of securing back members 1 and 2 in the closed or open position, I provide a latch 23 having one end pivotally mounted as by a pivot pin 24 in back member 55 1 and having its other end extending into back member 2.

Although I have not here shown a keeper for latch 23, I prefer to provide a slideable bar in back member 2 which is adapted to releasably engage notches in latch 23 as shown and described in my co-pending application heretofore referred to.

When the back members 1 and 2 of the binder are in the closed position and the 65 covers 6 and 8 are in the open position as

indicated on Figure 4 and it is then desired to open the back members, the latch 23 is released and the back members 1 and 2 are then moved about their hinge 3 into the position shown in Figure 5.

70 It will be obvious that during the movement of back members 1 and 2 about their hinge 3, the rollers 10 and 12 will move towards each other as will the rollers 11 and 13.

75 Similarly, when the back members 1 and 2 are in the open position as shown in Figure 5 and they are moved about their hinge 3 to bring them into the closed position shown in Figure 4, it will be obvious that the rollers 10 and 12 will be moved away from each other as will the rollers 11 and 13.

80 Inasmuch as all of the rollers 10, 11, 12 and 13 are free to rotate upon the shafts on which they are carried, these movements of opposed rollers towards and from each other will be accomplished with the minimum amount of friction between them and the 85 surface of the table on which the book is supported and therefore the manipulation of the binder to cause the back members 1 and 2 to be moved to the open or closed position will be accomplished with the minimum amount of energy and with the minimum 90 danger of any wear upon or damage to either the binder or the surface upon which it is supported.

95 In Figure 4, I have shown the two back members in the closed position and in Figure 5 I have shown them in the partially 100 open position with the ends of the opposed prongs in overlapping relation.

105 Although it is not here illustrated, it will be understood that the binder is so designed that it may be further opened to bring the ends of opposed prongs in spaced relation so that leaves may be placed on or removed from the prongs. It will also be understood that my invention may be used with various types of binders which employ hinged back 110 members for although I have shown and described a specific structure and form of part as an exemplification of an embodiment of my invention, I do not desire to restrict myself to the exact size, shape or relation of parts as various changes may be made within the scope of the appended claims.

115 I claim:

1. In a loose leaf binder, a pair of elongated back members having angular outer corners at the rear, hinge means connecting the inner edges of said back members, leaf-holding members carried by said back members and movable toward and from each other about said hinge means, each of said back members having an opening in its angular outer corner, rods mounted in said back members and extending across said openings, and a roller mounted on each of said rods and projecting rearwardly from the rear wall 120 125 130

of its respective back member and laterally from the side wall of its respective back member, so that in any position of movement of said back members about said hinge means, 5 the back members of the binder will rest on said rollers to facilitate opening and closing of the book.

2. In a loose leaf binder, a pair of elongated back members having angular outer corners at the rear, hinge means connecting the inner edges of said back members, leaf-holding members carried by said back members and movable toward and from each other about said hinge means, each of said back 15 members having openings in its angular outer corner, rods mounted in said back members and extending across said openings, pairs of spaced rollers mounted on said rods and said rollers projecting rearwardly from 20 the rear wall of their respective back members and laterally from the side wall of their respective back members so that in any position of movement of said back members about said hinge means the back members of the 25 binder will rest on said rollers to facilitate opening and closing of the book.

3. In a loose leaf binder, a pair of elongated back members having angular outer corners at the rear, hinge means connecting 30 the inner edges of said back members, leaf-holding members carried by said back members and movable toward and from each other about said hinge means, each of said back members having a pair of openings in its 35 angular outer corner, a rod mounted in each of said back members and extending across said openings, and a pair of spaced rollers mounted on each of said rods and projecting rearwardly from the rear wall of their 40 respective back members and laterally from the side wall of their respective back members so that in any position of movement of said back members about said hinge means the back members of the binder will rest on 45 said rollers to facilitate opening and closing of the book.

In witness whereof I have hereunto set my hand this 17 day of October, 1929.
